(57) **CLAIM**

The ornamental design for a stacking basket, as shown and described.

DESCRIPTION

FIG. 1 is a perspective view of a stacking basket showing my new design;

FIG. 2 is a front view thereof;

FIG. 3 is a side view thereof;

FIG. 4 is a top view thereof;

FIG. 5 is a bottom view thereof;

FIG. 6 is a perspective view of a stacking basket in stackable configuration;

FIG. 7 is a front view of the basket of FIG. 6;

FIG. 8 is a side view of the basket of FIG. 6; and,

FIG. 9 is a top view of the basket of FIG. 6.

The broken line showing is included for the purpose of illustrating portions of the article and forms no part of the claimed design.
